UNITED STATES PATENT OFFICE.

CHARLES ROHLS, OF BROOKLYN, NEW YORK, ASSIGNOR TO THE A. A. GRIFFING IRON COMPANY, OF JERSEY CITY, NEW JERSEY.

DESIGN FOR A HOT-CLOSET STEAM-RADIATOR.

SPECIFICATION forming part of Design No. 17,197, dated March 15, 1887.

Application filed January 28, 1887. Serial No. 225,601. Term of patent 7 years.

To all whom it may concern:

Be it known that I, CHARLES ROHLS, of Brooklyn, county of Kings, State of New York, assignor to the A. A. GRIFFING IRON COMPANY of Jersey City, State of New Jersey, have invented and produced a new and original Design for Hot-Closet Steam-Radiators, which is fully set forth in the following specification and accompanying drawing, in which is shown a front view of my newly-designed hot-closet steam-radiator.

The nature of my design is fully represented in the annexed drawing or illustration.

The general configuration of the design is that of a parallellopiped, or figure whose sides are parallelograms, the bottom part exhibiting a series of short loops surmounted by a

closet provided with doors and an interior shelf, the shelf and also the top and bottom of the closet being fret-work. The casing of the base and the top cornice are correspondingly ornamented, and on the doors are raised figures and knobs.

What I claim as my invention is—

A design for a hot-closet radiator in the form of a parallellopiped exhibiting a series of loops surmounted by a closet having a fret-work top, bottom, and interior shelf, substantially as described and shown.

CHARLES ROHLS.
